DESIGN FOR A WHEEL

Harry J. Horn, Lansing, Mich., assignor to Motor Wheel Corporation, Lansing, Mich., a corporation of Michigan

Application October 11, 1933, Serial No. 49,453

Term of patent 7 years

To all whom it may concern:

Be it known that I, Harry J. Horn, a citizen of the United States residing at Lansing, county of Ingham, State of Michigan, have invented a new, original, and ornamental Design for a Wheel, of which the following is a specification, reference being had to the accompanying drawing forming a part thereof.

In the drawings:

Figure I is a side view of a wheel showing my new design;

Figure II is a perspective view of the wheel body shown in Figure I;

Figure III is an enlarged sectional view through one of the spokes taken on substantially the line III—III of Figure I; and

Figure IV is a profile view of the wheel on substantially the line IV—IV of Figure I.

The wheel embodying the present invention includes a wheel body having a continuous periph-

eral band into which the spoke portions merge. The spokes are relatively short and spaced a substantial distance apart. The axially sloping side faces of the spokes accentuate the depth of the wheel. The front faces of the spokes are curved slightly and inclined to the radial plane of the wheel.

At their inner extremities the spokes merge with an annular portion constituting a smooth continuation of the spokes. The annular portion merges with a central portion which curves away from the portion in an axial direction. The hub cap preferably forms a smooth continuation of the central portion terminating near its center in a substantially flat surface.

I claim:

The ornamental design for a wheel as shown and described.

HARRY J. HORN.
